UNITED STATES PATENT OFFICE.

WILLIAM JOSEPH KYLE, OF PHILADELPHIA, PENNSYLVANIA, ASSIGNOR
TO KEYSTONE TELEPHONE COMPANY, OF PHILADELPHIA, PENNSYLVANIA, A CORPORATION OF NEW JERSEY.

ELECTRICAL TESTING APPARATUS.

SPECIFICATION forming part of Letters Patent No. 772,944, dated October 25, 1904.

Application filed November 19, 1902. Serial No. 132,038. (No model.)

To all whom it may concern:

Be it known that I, WILLIAM JOSEPH KYLE, of No. 2116 South Sixty-fifth street, Philadelphia, Pennsylvania, have invented certain new and useful Improvements in Electrical Testing Apparatus, whereof the following is a specification, reference being had to the accompanying drawings.

My invention is particularly designed for identifying individual conductors in cables including a plurality of conductors by charging a selected conductor with a current capable of producing a characteristic sound or tone in a telephone receiving instrument connected with that conductor. Such an operation is known as a "tone test" and is utilized in telephone practice in splicing cables, connecting up junction-boxes, and testing back to the cable-head in the telephone-exchange from manholes or other stations on the line. In the ordinary method of making such tone tests the testing-current is derived from an alternating-current generator located at the exchange-station, and the tester at the distant station, where said current is to be applied to the selected wire, is supplied with said current through any convenient circuit, usually one of the wires of the cable being tested. In such case it is necessary for the tester at the remote station to first telephone to the exchange operator to connect said generator with one of the wires of the cable. The tester must then determine which one of the several hundred wires of the cable contains the supply-current by connecting a telephone-receiver to each wire in succession until the supply-wire is found. The tester then makes connection between said supply-wire and any other wire to which the tone test is to be applied. Of course much time is wasted in securing the proper connections between the exchange-station and the temporary testing-station to thus supply the latter with the testing-current, and after such connection is apparently established it may be accidentally broken without the knowledge of the tester, who has no direct control of the apparatus. Moreover, such a method necessitates the em-

ployment of a current of such magnitude as to disturb all of the other circuits included in the cable, producing such a noise in each of them as to interfere with their use for the transmission of speech.

The present invention obviates the objections aforesaid by providing the tester with a portable apparatus comprising means to produce the desired tone upon any selected wire without the intervention of the operator at the exchange-station.

Certain advantages incident to the employment of my invention may be noted as follows: The waste of time hitherto necessary in establishing and maintaining a current-supply circuit between the exchange-station and the testing-station is obviated. The tone-current being produced under the direct control of the tester, the possibility of its supply-circuit being broken or disturbed without the knowledge of the tester is obviated, the testing-current being only required to traverse the length of the wire which is to be tested and without first traversing a supply-wire from the exchange-station to the testing-station. The current generated in the portable apparatus may be so small as not to create any disturbance or produce any noise in the wires of the cable other than the single wire being tested. Moreover, as hereinafter described, the testing-current is an induced pulsatory direct current, capable of producing a much more distinct tone than the alternating current heretofore employed without making the other wires in the cable noisy.

My invention comprehends the various novel features of construction and arrangement hereinafter more particularly described and claimed.

In the accompanying drawings, Figure I is a plan view of an organized apparatus embodying my invention. Fig. II is a vertical sectional view of said apparatus, taken on the line II II in Fig. I. Fig. III is a plan view of the casing and an inverted plan of the casting-lid shown in Figs. I and II. Fig. IV is a diagram showing a convenient arrangement of the wiring connections of said appa-

ratus. Fig. V is a diagram showing a modified arrangement of the wiring connections of said apparatus.

In said figures, 1 is the inclosing casing, 5 comprising the removable lid 2 and conveniently portable by the strap-handle 3. Said casing 1 incloses both the generator consisting of the plurality of battery-cells 5 and the condenser 7.

10 Conveniently mounted upon the under side of the lid 2 is the combined transformer and automatic circuit-breaker 9, provided with the primary terminals 11 12 and the secondary terminals 13 14. Said transformer comprises 15 the primary coil 16 and the secondary coil 17, which coils are conveniently divided, as shown in Fig. IV, and provided with the U-shaped core 18, whose poles are opposed to the oscillatory armature 19, which is pivoted at 20.

20 Upon the casing-lid 2 is mounted the switch-lever 22, which is arranged to oscillate upon the center 23 and to successively make contact with a plurality of terminals 24, respectively connected to individual battery-cells 5.

25 As best shown in Fig. IV, said cells 5 are connected by the circuit 25 with the primary coil 16, and said circuit includes the armature 19, switch-terminal 21, and switch-lever 22, so that in accordance with the position of the

30 switch-lever 22 a variable number of said cells may be included in circuit with said coil 16. It is to be understood that the arrangement is such that when said coil 16 is energized by any desired number of said cells 5 the armature 19 is vibrated, so as to automatically make and break said primary circuit 25.

The secondary coil 17 of the transformer 9 is connected by the secondary circuit 27 with the terminals 28 and 29, mounted upon the 40 casing-lid 2, and the condenser 7 is included in said circuit 27. Said terminals 28 and 29 are adapted to detachably connect with the external circuit 30 31, which is to be tested, and it is to be understood that the operation 45 of the device is such that the vibrations of the armature 19, making and breaking the primary circuit 25, induce a corresponding pulsatory current in the secondary circuit, including the exterior circuit 30, which is to 50 be tested, and thus produce a peculiar sound or tone in said exterior circuit. The switch-lever 22 is utilized to include only so many of the battery-cells 5 as suffice to produce the desired tone without disturbing other circuits 55 adjoining the particular circuit selected for the test, the current being thus increased or decreased in accordance with the length and resistance of the circuit being tested.

A second pair of terminals 33 34 are mounted 60 upon the lid 2 and adapted to detachably connect with an exterior circuit 35 36 to be tested. The circuit 37 38, extending from said terminals 33 34 within the casing 1, includes the switch 22, as shown in Fig. IV, 65 and (in accordance with the position of said

switch) includes a variable number of the battery-cells 5, so as to deliver a current upon the circuit 35 36 without producing a continuous sound or tone therein, the presence of the testing-current being manifested simply 70 by a click in a telephone-receiver when the tested circuit is connected therewith.

In the arrangement shown in Fig. IV the number of cells 5 in connection with both pairs of terminals is variable by means of the 75 switch-lever 22, and ordinarily the respective circuits to be tested would not be connected to said terminals at the same time, as indicated. However, as shown in Fig. II, entirely-separate groups of cells 5 are connected 80 with the respective pairs of terminals, the conductor 37 being disconnected from the switch-fulcrum 23 and being directly connected with the battery, as indicated in Fig. V, wherein the conductor 37 is provided with 85 a switch 26 for making and breaking the connection when desired.

The apparatus above described may be used for tone-testing a telephone-cable, as follows: The apparatus being taken to the manhole or 90 other temporary testing-station, (indicated at 40 in Fig. IV,) the tester calls up the operator at the exchange-station 41 on any working wire and gives notice that he is ready to test the cable 43, comprising, say, three hundred pairs of wires. The tester then connects his apparatus with any pair on the cable and, if it is an idle pair, continues speech communication with the exchange operator through the same, but if it is busy he proceeds until an idle pair is found. Communication for speech may then be established through the cable and by ground connection at the testing-station and at the exchange-station, it being noted, with reference to Fig. 105 IV, that by a ground connection 42 made at the exchange-station, the tone-producing apparatus may be short-circuited, as indicated, so as to suppress the tone with respect to the metallic circuit. The tester then proceeds to 110 connect the testing apparatus with each of the pairs in the cable in succession, and as connection is made with each pair the operator at the exchange-station ascertains by the tone which pair is thus connected and reports 115 the number of that pair to the tester in the manhole, who is thus enabled to identify the same.

It is to be understood that the condenser 7 so modifies the current from the testing-generator as to prevent the accidental operation of the telephone signaling devices in the exchange-station by said current-- that is to say, (with reference to Fig. IV,) when the switch-lever 22 is in contact with any one of the terminals 24 the current in the primary circuit is direct and pulsatory, whereas the current induced in the secondary circuit (including the tested line 30 31 and comprising both inductive resistance and capacity) has the char- 125 130

acteristics of an alternating current, incapable of operating the subscriber's annunciator signal at the exchange-station.

I do not desire to limit myself to the precise details of construction shown and described, as it is obvious that various modifications may be made therein without departing from the essential features of my invention.

I claim—

1. In a portable device constructed and arranged for testing electric circuits, the combination with an inclosing casing; of a generator within said casing; a transformer, comprising a primary and a secondary coil within said casing; a primary circuit including said generator and said primary coil; a movable armature arranged to automatically make and break said primary circuit; a secondary circuit, separate from said primary circuit and including said secondary coil; and, means, exterior to said casing, to detachably connect said secondary circuit, with the circuit to be tested including separate and distinct terminals for the primary and secondary circuits, substantially as set forth.

2. In a portable device constructed and arranged for testing electric circuits, the combination with an inclosing casing; of a generator within said casing; a transformer, comprising a primary and a secondary coil within said casing; a primary circuit including said generator and said primary coil; means to automatically make and break said primary circuit; a condenser within said casing; a secondary circuit, separate from said primary circuit and including said secondary coil; and, means exterior to said casing to detachably connect said secondary circuit with the circuit to be tested including separate and distinct terminals for the primary and secondary circuits, substantially as set forth.

3. In a portable device constructed and arranged for testing electric circuits, the combination with an inclosing casing; of a generator within said casing; means to vary the current from said generator; a transformer comprising primary and secondary coils within said casing; a primary circuit including said generator and said primary coil; means to automatically make and break said primary circuit; a secondary circuit separate from said primary circuit and including said secondary coil, and, means exterior to said casing to detachably connect said secondary circuit with the circuit which is to be tested including separate and distinct terminals for the primary and secondary circuits, substantially as set forth.

4. In a portable device constructed and arranged for testing electric circuits, the combination with an inclosing casing; of a generator within said casing; a transformer comprising concentric primary and secondary coils within said casing; a primary circuit including said generator and said primary coil;

an oscillatory armature, local to said transformer, included in said primary circuit, and arranged to automatically make and break the latter; a secondary circuit separate from said primary circuit and including said secondary coil; and, means, exterior to said casing, to detachably connect said secondary circuit with the circuit to be tested including separate and distinct terminals for the primary and secondary circuits, substantially as set forth.

5. In a portable device constructed and arranged for testing electric circuits, the combination with an inclosing casing; of a battery-cell detachably mounted within said casing; a transformer, comprising a primary coil and a secondary coil within said casing; a primary circuit connecting said battery and said primary coil; an oscillatory armature for said transformer, included in said primary circuit and arranged to automatically make and break the latter; a secondary circuit separate from said primary circuit and including said secondary coil; and, means exterior to said casing, to detachably connect said secondary circuit with the circuit to be tested including separate and distinct terminals for the primary and secondary circuits, substantially as set forth.

6. In a portable device constructed and arranged for testing electric circuits, the combination with an inclosing casing; of a battery within said casing, comprising a plurality of cells; a transformer, comprising a primary coil and a secondary coil within said casing; a primary circuit connecting said battery and said primary coil; means to vary the number of battery-cells included in said primary circuit; a movable armature for said transformer, included in said primary circuit and arranged to make and break the latter; a secondary circuit separate from said primary circuit and including said secondary coil; and, means exterior to said casing, to detachably connect said secondary circuit with the circuit to be tested, substantially as set forth.

7. In a portable device constructed and arranged for testing electric circuits, the combination with an inclosing casing comprising a removable lid; of a battery, comprising a plurality of cells within said casing; a condenser within said casing; a transformer, comprising primary and secondary coils within said casing; a primary circuit connecting said battery and said primary coil; a switch mounted upon the exterior of said casing and arranged to vary the number of battery-cells included in said primary circuit; a movable armature for said transformer, included in said primary circuit and arranged to automatically make and break the latter; a secondary circuit, separate from said primary circuit and including said secondary coil and said condenser; a pair of terminals for said secondary circuit, mounted upon the exterior of said casing and ar-

ranged to detachably connect with a circuit to be tested; a second pair of terminals, upon the exterior of said casing, arranged to detachably connect with a circuit to be tested; 5 and, circuit connections within said casing extending from the last-named terminals to said battery, substantially as set forth.

8. In a portable device constructed and arranged for testing electric circuits, the combination with an inclosing casing; of two pairs of terminals mounted upon said casing and respectively arranged to detachably connect with circuits to be tested; a generator within said casing; circuit connections between said 15 generator and both pairs of said terminals; means, within said casing, to supply one pair of terminals with a secondary current induced from said generator and having characteristics of an alternating current; and, means, 20 within said casing, to supply the other pair of said terminals with a direct current from said generator, substantially as set forth.

9. In a portable device constructed and arranged for testing electric circuits, the combination with an inclosing casing; of two pairs of terminals mounted upon said casing and respectively arranged to detachably connect said circuits to be tested; a generator within said casing; circuit connections between said 25 generator and both pairs of said terminals; means within said casing to supply one pair of terminals with a secondary current induced from said generator and having characteristics 30 of an alternating current, and, said second pair of terminals are supplied with a direct current from said generator, substantially as set forth.

ties of an alternating current; means within said casing to supply the other pair of said 35 terminals with a direct current from said generator; and, a switch carried by said casing arranged to control the connections between said terminals and said generator, substantially as set forth.

10. In a portable device constructed and arranged for testing electric circuits, the combination with an inclosing casing; of two pairs of terminals mounted upon said casing and respectively arranged to detachably connect 40 with circuits to be tested; of a generator within said casing; a condenser within said casing; interlinking primary and secondary circuit connections between said generator and one pair of said terminals, including said 45 condenser in the secondary circuit; and, primary circuit connections between said generator and the second pair of said terminals; whereby said first pair of terminals are supplied with a secondary current induced from 50 said generator and having characteristics of an alternating current, and, said second pair of terminals are supplied with a direct current from said generator, substantially as set forth.

In testimony whereof I have hereunto signed my name, at Philadelphia, Pennsylvania, this 13th day of November, 1902.

WILLIAM JOSEPH KYLE.
